UNITED STATES PATENT OFFICE.

WILLIAM L. CARD, OF MOBERLY, AND JAY NOBLE, OF ST. LOUIS, MISSOURI,
ASSIGNORS TO CARD AUTOMATIC BRAKE COMPANY.

AUTOMATIC CAR-BRAKE.

SPECIFICATION forming part of Letters Patent No. 223,317, dated January 6, 1880.

Application filed August 13, 1879.

To all whom it may concern:

Be it known that we, WILLIAM L. CARD, of Moberly, Randolph, State of Missouri, and JAY NOBLE, of the city of St. Louis, in 5 the State of Missouri, have invented certain new and useful Improvements in Automatic Car-Brakes, of which the following is a full, clear, and exact description, reference being had to the accompanying drawings, and to 10 the letters of reference marked thereon.

Our invention may be considered an improvement upon that described in Letters Patent granted to W. L. Card, and dated August 27, 1878, the same ends being accomplished, 15 but by means that vary from those described in the said patent.

In our present improvement the automatic effect is produced by means of a weighted revolving bar or frame pivoted to a sleeve, which 20 surrounds and is clamped upon the axle, and which has upon it an endwise-sliding collar, which is actuated by the revolving bar or frame. It also has a fixed collar of a similar form. The sliding collar acts through the medium of a lever upon the draw-plate or pull-rod through which the draw-lever acts upon the 25 brake-lever to set the brakes.

An important feature of the present improvement consists in the means by which a 30 suitable fulcrum is secured for the above-mentioned lever, which is actuated by the automatic device upon the axle, and controls the sidewise motion of the draw-plate or pull-rod.

It will be readily seen that when the brakes 35 are applied the trucks are held back and the body of the car will surge ahead of them one or more inches; also, that in passing over inequalities in the track and around curves the trucks will have an up-and-down and sidewise 40 motion independent of and to quite an extent different from that of the body of the car; and, further, that the relative position of the car body and axle is changed by loading and unloading, as well as by the side lurch of the car body upon the hangers independent of the 45 trucks. This fulcrum is obtained by means of a lazy bar or tongs similar in form to the lever under discussion, one end of which is secured to the floor-timbers of the car and partakes of all 50 the motions of the car, and the other end of which straddles the fixed collar of the auto-

matic device upon the axle and partakes of all the motions of said axle. The aforesaid lever may therefore be fulcrumed upon this lazy-tongs support at any point between where 55 it straddles the collar and where it is attached to the car-body, and the various independent movements of the car body or trucks will not interfere with the office of this lever to control the side motion of the draw-plate or pull- 60 rod.

Another important feature of the present improvement is the manner of constructing the draw-plate or pull-rod of a single piece; also, the manner of connecting it to the 65 bracket on the inner end of the draw-bar, so that it is free to oscillate in any and all directions.

Another new and important feature is the introduction of a grooved pulley in the outer 70 end of the lever, which communicates the power from the draw-bar to apply the brakes. It will be observed that one end of the chain which passes around this pulley is fastened to one of the car-timbers, and the other end is 75 attached to the brake-rod of the hand-brake mechanism. From the fact that the length of this lever is limited by the distance from the center (sidewise) of the car and the inner side of the car-wheels, (allowing for curvatures of track,) and the further fact that its throw is limited at its short end by the movement of the draw-bar, this pulley is introduced to increase the travel of the brake-rod, to 80 which the chain is attached.

By varying the relative position of the point at which the end of the chain is attached to the car-timbers and the fulcrum-pin of the lever which carries the pulley the travel of the 85 brake-rod may also be varied to quite an extent, and thereby adjusted to the conditions of the draw-bar which actuates it.

The construction of this apparatus is such as to make it easy of attachment to any car without injury to or change of any of its parts. 90

In the drawings, Figure 1 is an inverted plan of one end of a car-truck and car. Fig. 2 shows the revolving weighted bar or frame in side view, the axle in transverse section, and a side view of the lever. Fig. 3 is an enlarged view of the revolving bar or frame and the sleeve to which it is connected. Fig. 4 is 100

a side view of the brake-lever and grooved pulley. Fig. 5 is an enlarged view of the hooked pull-rod or draw-plate. Fig. 6 is a detail view, showing a modification of the 5 hook end of said arm. Fig. 7 is a detail view of the bracket which is attached to the inner end of the draw-bar, and which carries the pull-rod.

A is one end of the car-body. B B are the 10 ordinary draft-timbers secured to the bolster floor-timbers and end sill of the car, and in or upon which the draw-bar C has bearing and is attached, by means of lugs, followers, &c., in the usual manner, so as to admit of the 15 common endwise movement. D is a lug or bracket, which may be secured upon or attached to the rear part of the draw-bar by means of the bolt which passes longitudinally through the draw-bar pocket, and also the 20 spring and follower plates or other suitable bolts, for the purpose of connecting the inner end of the draw-plate or pull-rod E to the rear or inner end of the draw-bar C.

E is the draw-plate or pull-rod, the inner 25 end of which passes through the bracket D, and has a fixed collar, e, bearing against the outer side of the bracket, and a loose collar, F, which bears against the shoulder e' on the draw-plate or pull-rod, to prevent binding up- 30 on the bracket D, and thus allow a free movement to the pull-rod.

The loose collar F bears against a rubber or other suitable spring, G, which, in turn, bears against another collar, F', held on the inner 35 end of the draw-plate or pull-rod by a nut, F''. The draw-plate or pull-rod E has a side hook, H, to engage a pin, i, at one end of the brake-lever I, to actuate said lever by the inward movement of the draw-bar when the cars come 40 together.

The brake-lever I consists of two parallel bars, which straddle the fulcrum-bracket J attached to one of the draft-timbers.

j is the fulcrum-pin of the lever I. K is a 45 grooved wheel or roller at the opposite end of the brake-lever from the pin i. Around this roller passes a chain, L, one end of which is attached at a suitable point to the timbers of the car, and the other end of which is con- 50 nected to the ordinary brake-rod M.

N is a lever, connected at one end by a rod, O, to the end of the pull-rod E. The other end of this lever has a yoke, n n, which embraces the sliding collar P upon the sleeve Q, which 55 is made in duplicate halves and clamped upon the axle R by suitable lugs and bolts q and set-screws q'. This yoke rests in a circumferential groove in the collar P, so that the sliding movement of the collar causes an oscillation of the lever N. The collar P is made in duplicate halves, which are secured together around the sleeve Q by lugs and bolts q'.

S is a single or double plate or link, one end of which is secured by a loose pivot-joint to 60 the lazy bar or tongs Y near its center, the other end of said plate or link being secured

in a similar manner to the lever N, as shown in Fig. 1, and thus constitutes the fulcrum for the lever N, as well as a support, by means of the spring w', as shown in Fig. 2, for both the 70 lever and the lazy-bar.

Y is the lazy bar or tongs, one end of which is secured at a suitable point and in a suitable manner to the under side of the car body or timbers, and having at the other end a yoke, t t, 75 which embraces and is carried in a circumferential groove of the collar U, fixed upon the sleeve Q.

V is a link, connecting the sliding collar P to the weighted bar or frame W, pivoted upon 80 a shoulder or pin, w, extending radially from the sleeve Q. There are two of the links V, one on either side of the sleeve, connecting each bar of the frame W to opposite sides of the collar P.

O is a short connecting rod or link, which connects the end of the lever N to the end of the pull-rod E, its length being varied by nuts, as shown.

X X are weights at the ends of the frame 90 W, secured by bolts, as shown, the purpose of which is to cause the frame W to assume a position nearly at right angles to the axle when the axle and the sleeve Q upon it are rotating at ordinary speed. This position of the frame W 95 pushes the sliding collar P to the position shown in Fig. 3, and through the described means brings the hook H into line of engagement with the pin i, so that when the cars are running and the engine is checked up, so that the 100 draw-bars are driven inward, the brakes are set by the described means.

y are spiral springs, of which there are two, connected at one end to the collar P on the sleeve Q and at the other end to the frame W 105 upon the end opposite to that to which the link V is connected. The action of the spring y is to draw the weighted frame W and collar P into the position shown in Fig. 1 on the stoppage of the cars and consequent cessation of rotation of the axle with its sleeve Q. This movement of the frame W throws the hook H out of 110 line of engagement with the pin i, so that the cars may be moved forward and backward at a slow speed without the brakes becoming set 115 by the inward movement of the draw-bar; but as soon as the movement of the car attains an ordinary running speed the frame W assumes the position shown in Fig. 3, and then the inward movement of the draw-bar causes the 120 application of the brakes Z to the wheels a. It should be borne in mind, however, that when the train has stopped and the hook H is disengaged from the pin i of the lever I, as described, then, if the train is backed, an inward movement of 125 the draw-bar takes place, which carries the hook H to the inner side of the pin i, thus preventing its engagement therewith so long as the engine continues to push backward; but, upon shutting off steam and allowing the train 130 to stretch, the hook H will immediately engage with the pin i, and the setting of the brakes

on the forward car will immediately set all the rest.

The yoke ends of the lever N and lazy-bar Y are suspended upon a spiral spring, n' , or 5 other suitable support, to lessen the friction of the yokes in their bearings.

It will be observed that some of the attachments are made to the car-body A and others to the truck-frame b and axle R. Consequently 10 there must be some freedom of movement in the various parts to accommodate the movement of the car relatively to the truck. For this purpose the yokes n and t are elongated, as shown, and the various joints are so 15 constructed as to allow the necessary freedom of movement.

In Fig. 6 is shown a modification of the hooked end of the pull-rod E. In this there is a closed slot, e' , in which the pin i works, 20 the hook H projecting from one side of the slot.

As another modification, it is obvious that the weighted frame W may be located at the opposite side of the sleeve P to that on which 25 it is shown and described, the connecting parts being slightly modified to accord with the change in position. Also, that the automatic device upon the axle, consisting of the sleeve Q, frame W, lever N, lazy-bar Y, &c., 30 may be changed over onto the inner axle of the truck, and one end of the lever N connected to the extreme inner end of the pull-rod E, with but slight modifications, if desired.

35 The prongs n and t of the lever N and Y of the lazy-bar Y may be covered with rawhide to prevent wear; or an iron, steel, or brass tube may be slid on over them to receive the wear, and be renewed when worn out. The same 40 object may be accomplished with the collars U and P by lining them with rawhide or a suitable metallic lining.

The sleeve Q may be fastened upon the axle by winding upon said axle either rubber packing, 45 heavy packing-paper, or other suitable material sufficient to cause a proper resistance when the sleeve is clamped thereon by means of bolts through the lugs q .

The hook H may be made of steel, separate 50 from the pull-rod E, and so constructed as to be easily attached to and removed therefrom.

The collar e upon the pull-rod E may be made adjustable, if desired.

The spring G may be compressed so as to 55 afford any required resistance without clamping or binding upon the bracket D, as the pressure is received upon the shoulder e'' .

We claim as our invention—

1. The combination of the lever N, yoke 60 n , fulcrum-link S, spring n' , lazy-bar Y, yoke t , link O, and pull-rod E, substantially as set forth.

2. The automatic device or governor 65 consisting of frame W, weights X, connecting the two arms of said frame at each end, slid-

ing collar P, sleeve Q, springs y , link V, and attached to the axle of a railway-car for transmitting power by means of suitable transmitting-bars and connections, thereby coupling and uncoupling the draw-bar of a railroad-car 70 from the brake mechanism.

3. The brake-lever I, consisting of two parallel bars, grooved pulley K, secured within one end thereof, fulcrum-bracket J, chain L, attached at one end to the timbers of the car 75 and at the other end to the brake-rod, substantially as set forth.

4. The draw-rod E, provided with fixed collar e , loose collars F F', spring G, shoulder e'' , and nut F^2 , for coupling said rod to the bracket 80 D, substantially as and for the purposes set forth.

5. The combination of the axle R, sleeve Q, weighted frame W, link V, spring y , sliding collar P, and fixed collar U with the lazy-bar 85 Y, fulcrum-link S, spring-hanger n' , and lever N, substantially as and for the purpose set forth.

6. The combination of the axle R, sleeve Q, weighted frame W, link V, spring y , sliding 90 collar P, fixed collar U, lazy-bar Y, fulcrum-link S, and lever N with connecting-rod O, pull-rod E, bracket D, and the draw-bar of a railroad-car, substantially as set forth.

7. The combination of the axle R, sleeve Q, weighted frame W, link V, spring y , sliding 95 collar P, fixed collar U, lazy-lever Y, fulcrum-link S, lever N, connecting-rod O, hooked pull-rod E, bracket D, and draw-bar C with the lever I, fulcrumed at i upon the bracket J, 100 bolted to one of the draft-timbers of a railroad-car, substantially as set forth.

8. The combination of the axle R, sleeve Q, weighted frame W, link V, spring y , sliding 105 collar P, fixed collar U, lazy-bar Y, fulcrum-link S, spring-hanger n' , lever N, connecting-rod O, hooked pull-rod E, lever I, grooved pulley K, and chain L with the ordinary hand-brake mechanism of a railroad-car, substantially as and for the purpose set forth. 110

9. The combination of the lever N, having yokes n and t , sliding collar P, and governor-sleeve Q, substantially as and for the purpose set forth.

10. The combination, in an automatic car-brake mechanism, of the governor-sleeve Q, formed in two pieces, and provided with ears and bolts q and set-screws q' , by which they are secured together and attached to the axle, substantially as set forth. 115

11. The pull-rod E, formed with a hook, H, as shown and described.
